UNITED STATES PATENT OFFICE.

JESSE B. STORMS, OF LOCKPORT, NEW YORK.

MOLD FOR FENCEPOSTS.

Application filed April 18, 1922. Serial No. 554,553.

To all whom it may concern:

Be it known that I, JESSE B. STORMS, a citizen of the United States, residing at Lockport, in the county of Niagara and State of New York, have invented a new and useful Mold for Fenceposts, of which the following is a specification.

The device forming the subject matter of this application is adapted to be employed for the fashioning of concrete fence posts and like structures although the novel device of the present invention may be applied to molding structures of widely different types.

15 The present invention aims to provide a means for forcing the side walls of the mold apart and for drawing the side walls together, this means including an element having limited movement with respect to one 20 side wall, thereby permitting the actuating lever to move out of knuckling engagement with one side wall before the side walls are forced positively apart. A further object of 25 the invention is to provide novel means whereby one of the end walls is mounted between the side walls and held in place therebetween. A further object of the invention is to improve generally, the mechanism whereby the side walls of the mold are 30 spaced apart and brought together.

With the foregoing and other objects in view which will appear as the description proceeds, the invention resides in the combination and arrangement of parts and in 35 the details of construction hereinafter described and claimed, it being understood that changes in the precise embodiment of the invention herein disclosed can be made within the scope of what is claimed without departing from the spirit of the invention.

40 In the accompanying drawings:—

Figure 1 shows in perspective a mold constructed in accordance with the present invention;

45 Figure 2 is a top plan of the structure depicted in Figure 1;

Figure 3 is an end elevation of the structure shown in Figure 1, the actuating lever being disposed in that position which it will 50 assume when the walls of the mold are forced apart; and

Figure 4 is a perspective of the product which the mold is adapted to fashion;

55 Figure 5 is a detail perspective of the primary attaching member; and

Figure 6 is a detail perspective of the link which is removable with the primary attaching member.

In carrying out the invention there is provided a primary side wall 1 and a secondary wall 2. At each end of the mold duplicate structures are provided for the purpose of separating the side walls 1 and 2 for the purpose of drawing them together. But one of these structures will be described in detail.

Applied to the outer face of the primary side wall 1 and secured thereto by means of screws or bolts 3 is a primary attaching member 4 having an angular extension 5 disposed transversely of the end face of the primary wall 1. The secondary attaching member 6 is secured to the other side face of the secondary wall 2, the secondary attaching member 6 being provided with a protruding end 7 projecting beyond the adjacent end face of the secondary wall 2. The supporting member, preferably taking the form of a threaded element is extended through the protruding end 7 of the attaching member 6, the supporting member being denoted by the numeral 8. There are nuts N upon the supporting member 8, the nuts N engaging opposite faces of the protruding end 7 of the secondary attaching member 6, thereby to provide for an adjustment of the supporting member 6 and the inner end of the supporting member 8 is upturned.

As indicated in Figure 3, the end 9 carries the pivot 10 constituting a fulcrum for one end of the lever 11. A pivot 12 is located intermediate the ends of the lever 11, the pivot 12 being connected with the inner end of a link 14, the outer end of the link 14 being united by a pivot element 15 with the angular extension 5 of the primary attaching member 4. Projecting from the angular extension 5 of the attaching member 4 is a stud 16, adapted to be received in a slot 17 formed in the upper edge of the link 14.

The side walls 1 and 2 are equipped adjacent one end with recesses 18 receiving the end wall 19. The side walls 1 and 2 are equipped adjacent the other end with recesses 20, the recesses 20 are each supplied with seats 21, against which the wall 22 is adapted to rest. It is to be noted that the walls 23 and 24 flare toward the longitudinal side of the mold, the walls 23 converging towards the seats 21. Owing to the fact that

the walls 23 converge towards the seats 21, the walls constituting a means for guiding the end wall 22 into the seats 21, to form an anchor on the bottom of post.

5 It is to be observed that the attaching members 4 and 6 extend past the recesses 18 at the other end of the mold. Therefore, the attaching members 4 and 6 serve to enforce the side walls 1 and 2 and to set the 10 weakening of the side walls which is incident to the formation of the recesses 18 and 20.

Secured to one of the side walls, preferably to the side wall 1, is a plate 25 to which 15 is pivoted one end of a yoke 26, the free end of which is adapted to engage the outer face of the secondary wall 2, to reinforce the walls and to prevent them from springing apart during the molding operation.

20 In practical operation, the walls 1 and 2 are spaced upon a suitable pallet (not shown) in Fig. 3, the lever 11 is swung over in the direction of the arrow A until one edge of the lever 11 rests upon the upper 25 edge of the protruding end 7 of the secondary attaching member 6. When the lever is thus positioned, the pivot 12 which connects the lever 11 with the link 14 will be disposed below the pivot 10, which connects 30 the lever 11 with the up-turned end 9 of the supporting member 8, formation of the up-turned end 9 permitting this relation between the pivots 10 and 12. The lever 11 and the link 14 will, therefore, be disposed 35 in knuckled relation so that the separation of the side walls 1 and 2 will be possible only when the lever 11 is manipulated manually.

When it is desired to separate the walls 1 and 2 the lever 11 is swung in a direction 40 opposite to that indicated by the arrow A. Owing to the fact that the link 14 is slotted as shown at 17 to receive the stud 16, the link 14 will have a slight movement before the stud 16 engages with the link. This 45 slight movement will permit the lever 11 to rise at its free end sufficiently to lift the pivot element 12 above the pivot element 10, thereby permitting the lever 11 and the link 14 to move out of locked relation. Subsequently, the stud 16 will come into contact 50 with the link 14 at the base of the slot or notch 17, as shown in Figure 3, whereupon, if the lever 11 be swung at its free end in a direction opposite to that indicated by the 55 arrow A, the walls 1 and 2 will be forced apart.

The manner of mounting the end walls in

place, notably the manner of mounting the end wall 22, has been dealt with specifically hereinbefore, and these operations will be 60 thoroughly understood without further description.

The side walls 1 and 2 converge slightly, and when the concrete is dumped between the walls 1 and 2 and tamped down therebetween, the base indicated by the numeral 65 30 in Figure 4, will be formed. Owing to the fact that the walls 23 and 24 of the recesses 20 flare toward the longitudinal center of the mold, the head 32 may be removed 70 from the mold. It is to be noted that although the faces 23 and 24 converge, they do not meet at a sharp angle. Consequently the side walls of the head 32 which forms an anchor on the bottom of post are blunt, as 75 indicated at 33, there being no sharp angle in the head 32 at this point which angle, of course, can not be readily chipped off, and broken in use and in the removal of the mold from the post.

Having thus described the invention what is claimed is:—

A mold comprising primary and secondary side walls, the walls having recesses in 80 their inner faces, an end wall held in the recesses at one end of the recesses, attaching means at each end of the walls, each attaching means comprising a primary and secondary attaching member, a projection formed on each primary attaching member, a supporting member longitudinally adjustable on the secondary attaching member, means on the supporting member for holding the same in adjusted position upon the secondary attaching member, a link pivotally connected to the primary attaching member and 85 adapted to engage the projection to space the walls apart, the supporting member having an angular end, a lever pivoted to the link and having pivotal connection with the angular end to move below the pivotal connection between the levers, and said angular end, and the secondary attaching member constituting a stop for preventing a downward movement of the free end of the lever. 95

In testimony that I claim the foregoing as my own, I have hereto affixed my signature in the presence of two witnesses.

JESSE B. STORMS.
